IMPROVEMENT IN PRUNING KNIVES.

L. B. MORRIS, OF HOPKINSVILLE, KENTUCKY.

Letters Patent No. 60,225, dated December 4, 1866.

SPECIFICATION.

TO ALL WHOM IT MAY CONCERN:

Be it known that I, L. B. MORRIS, of Hopkinsville, in the county of Christian, and State of Kentucky, have invented certain new and useful improvements in the manner of constructing Pocket Knives; and I do hereby declare that the following is a full, clear, and exact description thereof, reference being had to the accompanying drawings, making part of this specification, and to the letters of reference marked thereon, like letters indicating like parts wherever they occur on the drawings.

To enable others skilled in the art to construct and use my invention, I will proceed to describe it.

Figure 1 is a side view of a knife made on my plan, and having a portion of the handle broken away to show the inside.

Figure 2 is a back view of a double-bladed knife, open; and

Figure 3 is a plan view of the two sides of the handle, detached.

My invention has for its object the construction of a knife, in which the blade shall be fixed or rigid, both when open and when shut, and which can be opened or closed at will.

A represents the handle, to which the blade B is pivoted in the usual manner, as shown in fig. 1. The pivoted end of the blade is formed on a circle, as shown by *h*; and on the back, at a point near the end of the handle, a notch, *l*, is formed, as shown in fig. 1, for the reception of the lug or projection *i*, formed on the handle at that point, as shown more clearly in the upper portion of fig. 3, which represents that portion of the handle detached. On the under side of the blade another notch or shoulder, *d*, is formed, against which the lug or projection *n*, attached to the opposite side of the handle, comes in contact, when the knife is open, the position of the lug *n* being shown clearly in the lower portion of fig. 3, and also in position against the shoulder *d*, in fig. 1. The blade B is inserted between the handles A, and pivoted, that being the only point at which the handles are firmly united, the opposite ends being left loose, so that the two parts can be opened at the lower end, and turned around on the pivot that unites them at the opposite end. A stud or pin, *o*, is attached to one side of the handle, on the inside, as shown in fig. 1, against which the blade rests when closed, as shown red. In or on one of the sides of the handle a spring, *a*, is secured, which, springing outward, engages in a notch in the under side of a piece, *c*, which is attached to the other part of the handle, and projects over the end of the spring *a*, as shown in the various figures. A projection, *e*, is secured upon the outer surface of the spring *a*, as shown in figs. 1 and 2, for the thumb or finger to press upon, in order to depress the spring and readily open the parts. To open the knife, it is only necessary to unloose the catch or spring *a*, and swing one of the sides of the handle around in a circle, upon the pivot, by which operation the blade will be opened, and as the handles are brought into place and secured, the lug *i* will fit in the notch *l*, on the back of the blade, while the lug *n*, on the opposite side, will fit snug against the shoulder *d*, on the front of the blade, and thus hold it rigidly and securely in place. To close the knife, it is only necessary to reverse the operation. It is obvious that, if desired, the plates of the handle may be covered with wood, horn, or other suitable material, the point *e* protruding through it so as to be operated by the thumb or finger. The catch *a*, instead of being arranged to operate as shown, may be arranged to slide lengthwise, like a bolt, or in any suitable manner, to secure the parts in position. Fig. 2 represents the back of a double-bladed knife, constructed on this plan, the two outside plates of the handle being, in this case, duplicate, each having the projection *i* thereon, while the projection *n* is attached to the central plate on each side. It is obvious that these projections may be attached to either plate, the only requisite being that they should be so located as to fit into the notches or recesses in the blade, when opened. By these means, I am enabled to construct a knife that is very strong, and that cannot be accidentally closed or opened, and that is specially well adapted to a pocket pruning knife.

Having thus described my invention, what I claim, is—

A knife having its blade provided with the notches or recesses *l* and *d*, and a handle having the projections *i* and *n*, arranged to fit therein, as shown and described.

L. B. MORRIS.
